HIGH FREQUENCY SIGNAL TRANSMISSION CIRCUITS

Application filed October 12, 1927. Serial No. 225,823.

Our invention relates broadly to electron tube amplifier systems and more particularly to a circuit arrangements for a high power high frequency amplification system.

One of the objects of our invention is to provide a circuit arrangement for a high power frequency amplifier system in which a balanced operation of the circuits may be obtained without the establishment of parasitic oscillations in the tube circuits.

Another object of our invention is to provide a coupling system for the circuits of electron tubes wherein the nodal points of the signaling currents can be fixed in predetermined positions and oscillating surges in opposition to normal amplification of the signaling currents avoided.

Our invention will be more clearly understood from the specification hereinafter following by reference to the accompanying drawings wherein:

Figure 1 illustrates the type of electron tube circuit to which our invention may be applied; Fig. 2 shows the application of the circuit arrangement of our invention to the electron tube circuit of Fig. 1; Fig. 3 shows a coupling system of the type to which the circuit of our invention may be applied; and Fig. 4 illustrates the application of our invention as a coupling system for a plurality of electron tubes in a high power high frequency amplifier system.

In order to understand the advantages of our improved type of balance circuit in its application to tubes which have relatively high internal capacities and which are to be operated at very high frequencies, it will be advisable to review briefly the behavior of older types of balance circuits and explain why they fail to work on such tubes and are unsatisfactory on all tubes when such tubes are operated at a very high frequency.

Figure 1 shows a tube which is balanced on itself by one of the methods already known to the art. The grid of this tube receives its excitation at a frequency, say "F" at the point marked "EX". It is assumed that this excitation comes from a master oscillator of constant frequency, which may or may not be piezo electrically controlled. The plate

circuit of this tube is tuned to resonance to the frequency "F" or to 2-F, or higher harmonic frequencies of the excitation frequency by means of a variable plate circuit inductance and a variable condenser C₁. Means are provided for varying the number of plate turns, the number of tuning turns and the tap which carries energy from this circuit to the load. The load may be another amplifier tube of higher power or it may be an antenna system or any other form of useful load. In order to prevent this tube from executing self-oscillations it is balanced on itself by means of a variable balancing condenser B₁, which connects between the grid and a point on the plate circuit coil system which is below ground potential, which means for practical purposes below filament potential.

The voltage in this lower portion of the coil below the ground potential point is in opposite phase to the voltage above this point, and therefore, the internal feed-back through the tube may be neutralized by adjusting the number of turns below ground and by adjusting the balanced condenser B₁. The condenser shown at "S" is merely a stopping condenser of relatively large capacity. Now, this circuit has been persistently tried for operation with tubes of 250 watt output and higher with very indifferent results when the output frequency of said tubes is in excess of 12,000 kcs. and with no apparent balance at all possible at frequencies between 16,000 and 20,000 kcs.

An examination of the circuit when in operation at very high frequencies by means of a voltage indicator instrument of very low capacity shows that the voltages on the plate coil did not pass through a node or zero potential point even when the coil was explored several turns below the connection which leads to filaments and ground. Although this seems at first surprising, it is readily understandable when it is considered that at these very high frequencies the total number of turns in that portion of the plate coil system which is tuned by the condenser C₁, is reduced to sometimes as low as two turns, depending on the diameter of the coil system. For instance, with a coil about 2 1/2" in diameter, 1/4" wide cop-

per strap, turns separated about $\frac{1}{4}$ of an inch apart and using a 250 watt tube and operating at 16,000 kcs. there are generally not over four turns in the tuned portion of the plate coil systems. In the case of the 1 k. w. air-cooled tube which has very high internal capacity there are about the same number of turns at the same frequency with straps 1" wide of even smaller inductance. It is, 10 of course, impossible to wire these circuits up without having at least a good many inches of lead wire between the coil system and the ground and under conditions like these, the actual nodal point does not lie in the coil system at all. On account of there 15 being a very material drop of potential over the ground leads (leads to filaments), it might be considered that by adding a sufficient number of balance turns this difficulty would be 20 ultimately overcome, but this has been found experimentally to be fallacious, the reason being that after the first three or four turns there is so little coupling between the added turns and the small number of turns in the 25 tunable portion of the coil that very little, if any, electromotive force is produced in the balance turns after the first few turns. If, then, a reversed potential point cannot be 30 found in the first few turns which are in series with the balanced condenser, they will 35 not be found at all. To put it another way, the positive drop in voltage over the inevitable ground lead cannot be overcome by the reversed potential existing in the balance turns connected through the balancing condenser B_1 . This difficulty does not occur 40 except at very high frequencies and it is a difficulty which is greatly aggravated by the use of tubes of large internal capacity, because the number of turns in coils which can 45 be used in the tuned portion of the plate circuit is smaller with such tubes than with others, thereby reducing the coupling between tuned portions of the plate coil and the lower end of the coil which is used for balance 50 turns. This analysis of the situation agrees both with theory and facts as determined by experiments.

Fig. 2 shows one method in which it has 55 been possible to correct this inherent difficulty and extend this balance circuit to the operation of such high capacity tubes at very high frequencies. The modification is extremely simple but extremely important since it makes 60 for the difference between success and failure in the operation of such tubes at such frequencies. In order to get more efficient coupling with the balance turns the lower terminal 10 of the condenser C_1 is dropped below the lead 11 which goes to filaments and ground so that under these conditions neither side of the condenser C_1 is connected to ground. Under these circumstances there is 65 bound to be a nodal point of potential in the plate coil system 12 and the balance op-

eration can be carried out successfully. Fig. 3 shows one of the older methods of balancing an amplifier tube not against itself but against the next succeeding tube in the amplification system. A tube 14 excited at a 70 very high frequency at the point "EX" is shown on the left of this diagram and a typical balance circuit connecting it with the 75 succeeding tube 15 of higher power is shown to the right. The plate coil system 12 of the 80 left hand tube is shown with tap which leads through a stopping condenser S_1 to the grid of the next amplifier 15 thereby delivering excitation voltage to that grid. To offset that portion of the energy which would pass 85 through the internal coupling of the right hand tube 15 and thence into the plate circuit of the right hand tube 15, the balance condenser B_3 is connected to a point below ground on the plate coil system 12 of the left 90 hand tube 14 and on the other hand, to the plate of the right hand tube 15. There is a stopping condenser S_2 of relatively large capacity in series with the balance condenser B_3 , but as far as the electrical high frequency 95 behavior of the circuit is concerned, the balance condenser B_3 may be considered as connected directly to the plate of the right hand tube 15. In the circuit of Fig. 3 it is assumed that it is a straight balance on a 100 given frequency. There is no frequency doubling involved in this circuit as there was in Figs. 1 and 2. For the purpose of illustrating our invention it may be assumed that the left hand tube 14 is a 250 watt tube and 105 that the right hand tube 15 is a 1 k. w. air-cooled tube or a water-cooled tube and that the excitation frequency developed in the left hand tube is high, say in the neighborhood of, for instance, 15,000 to 20,000 kcs. The 110 development of this frequency in the left hand tube 14 can be by a process of frequency doubling but from the left hand tube there is no further multiplication of frequency. The excitation to the left hand tube might 115 be, for instance, 8,000 kcs. whereas the plate circuit tunable by means of condenser C_3 might bring out the second harmonic at 16,000 kcs., but when the energy is taken off from the coil system 12 to excite the right hand 120 tube 15, the balance system must operate the right hand tube 15 at the same frequency as the left hand tube; namely, at 16,000 kcs. In other words, the right hand tube is excited 125 at the same frequency that it puts out and is, therefore balanced at this frequency against the preceding tube. Now, this balanced circuit as shown in Fig. 3 has been repeatedly tried with indifferent results at 12,000 kcs. and with absolute failure at higher frequencies. It fails for exactly the same reason given for the failure of the circuit in Fig. 1; namely, that it is impossible to get a reversed potential across the balance condenser B_3 , which can be utilized to neutralize the energy 130

fed between grid and plate of the right hand tube. The method of correcting this difficulty is similar to the method followed in the other circuits as shown in Fig. 2; namely, referring now to Fig. 4, the tuning condenser C_4 on the left hand tube has one terminal 10 brought below the terminal 11 which connects the coil system to filaments and ground, and this change makes again for the difference between failure and success. A further extension of this principle is shown in Fig. 4 in the valve output circuits of the right hand tube 15. In Fig. 3 the output circuit of the right hand tube 15 is tuned by means of a condenser C'_3 which connects across certain turns of the plate coil system 16 and the ground, but in Fig. 4 a similar condenser C'_4 is connected across a portion of the coil 16, part of which lies above the lead 17 connecting the ground and filament and part below the connection point 17. This enables the balance system to be carried through a succeeding or third power amplifier tube, or a connection to a load such as an antenna above the nodal point of the plate coil system 16 and at the same time a load such as a counterpoise at a point below the nodal point of the plate coil system 16 may be provided, a procedure which is often useful in the art. It should be clearly understood that these changes are very important as far as practical operation is concerned and vitally necessary. It should be understood that Figs. 1 and 3 have been illustrated only for purposes of clarification and comparison. The new circuits of Figs. 2 and 4 have increased the availability of high power and all water-cooled tubes for power amplifier work in the higher frequency band. The circuits of Figs. 2 and 4 are also a great advantage for tubes of low internal capacity in improving their performance.

The arrangement of the tap in the plate circuit inductance is such as to force a heavy circulatory current to come lower in the coil, and such current is accompanied by a reverse potential with respect to the potential in the plate current inductance proper, thereby suppressing oscillatory currents. Both sides of the tuning condenser are insulated from ground potential by the provision of the circuit arrangement shown, and this condition facilitates tuning and adjustment of the circuits without shock to the operator.

The circuit arrangements described herein have been developed and tested under extended service conditions and have been found to give excellent results.

While we have described the invention in its preferred embodiment we desire that it be understood that modifications may be made and that no limitations upon the invention are intended other than are imposed by the scope of the appended claims.

What we claim as new and desire to secure

by Letters Patent of the United States is as follows:

1. A transmission system for high frequency currents comprising a plurality of electron tubes each having an input circuit connected between the grid and cathode electrodes thereof, and an output circuit connected between the plate and cathode thereof, an inductance coil providing a coupling medium between the output circuit of one electron tube and the input circuit of a succeeding electron tube, a connection extending from the cathode electrode in the output circuit of one electron tube to a tap along said inductance intermediate its ends, a variable capacity element having one side thereof connected to a point in said inductance on one side of said tap and having the opposite side thereof connected to a point in said inductance on the other side of said tap, said taps being disposed intermediate the ends of said inductance, and a balancing circuit connected to said inductance at a point remote from the point to which said last named side of said variable capacity element is connected for stabilizing the operation of the transmission system at high radio frequencies.

2. In a high frequency signal transmission system a plurality of electron tubes each having grid, cathode and plate electrodes, an output circuit included between the plate and cathode electrodes of each of said tubes, an input circuit extending between the grid and cathode electrodes of each of said tubes, an inductance having portions thereof connected in common between the output circuit of one tube and the input circuit of a succeeding tube, the output circuit of one tube terminating at a tapped connection in said inductance intermediate the ends thereof, a variable condenser system having one side thereof connected with said inductance at a position on one side of said tapped connection the other side of said condenser system being connected with said inductance at a position on the other side of said tapped connection, and a balancing circuit connected to said inductance remote from the last mentioned side of said variable condenser system and outside of the circuit formed through said condenser, for establishing a circulatory current path in a direction opposite to the normal current flow accompanying the transfer of energy from said output circuit to said input circuit and balancing the operation of said circuits.

3. In a signal transmission system a plurality of electron tubes each having grid, cathode and plate electrodes, an output circuit including the plate and cathode electrodes of one electron tube, an input circuit including the grid and cathode electrodes of a succeeding electron tube, an inductance, a connection extending from the cathode electrode in said output circuit to a tap on said

- inductance intermediate the ends thereof, connections extending from said input and output circuits to points on said inductance, a tuned circuit comprising a portion of said inductance on one side of said tap and a portion on the other side of said tap, and a balancing condenser, one side of which is connected to said inductance beyond the limits of said tuned circuit and the other side of which is connected to the input circuit of said electron tube for opposing the tendency of said circuits to be set in a condition of parasitic oscillations.
4. In a signal transmission system, an electron tube having grid, cathode and plate electrodes, a plate circuit inductance having a tap coupled to said plate electrode, a second tap on said inductance connected to said cathode electrode, a balancing condenser, a third tap on said inductance connected in circuit with said balancing condenser and said grid electrode, and a plate circuit tuning condenser connected in parallel with a portion of said plate circuit inductance by taps thereto one of which is interposed between said plate circuit tap and said cathode circuit tap and the other of which is on the opposite side of said cathode circuit tap between the latter and said balancing condenser tap.
5. In a signal transmission system, an electron tube having grid, cathode and plate electrodes, an output circuit including the plate and cathode electrodes of said tube, an input circuit including the grid and cathode electrodes of said tube, an inductance, a connection extending from the cathode electrode in said output circuit to a tap on said inductance, connections extending from said input and output circuits to points on said inductance, a tuned circuit comprising in part an intermediate portion only of said inductance, part of which is on one side of said tap and the other part of which is on the other side of said tap, and a balancing condenser one electrode of which is connected to said inductance outside of said portion comprising said tuned circuit and the other electrode of which is connected to the input circuit of said tube for opposing the tendency of said circuits to be set in a condition of parasitic oscillation.

In testimony whereof we affix our signatures.

ALBERT H. TAYLOR.
